UNITED STATES PATENT OFFICE.

EDGAR F. HATHAWAY AND CHARLES LEA, OF BOSTON, MASSACHUSETTS, ASSIGNEES TO
AMERICAN WARP DRAWING MACHINE COMPANY, A CORPORATION OF MAINE.

WARP-REPLENISHING MACHINE.

1,304,875.

Specification of Letters Patent.

Patented May 27, 1919.

Application filed October 30, 1911. Serial No. 657,628.

To all whom it may concern:

Be it known that we, EDGAR F. HATHAWAY and CHARLES LEA, both citizens of the United States, and residents of Boston, county of Suffolk, Commonwealth of Massachusetts, (whose post-office addresses are 195 Freeport street, Dorchester, Massachusetts,) have invented an Improvement in Warp-Replenishing Machines, of which the following description, in connection with the accompanying drawings, is a specification, like characters on the drawings representing like parts.

This invention relates to improvements in warp replenishing machine, and has particular reference to apparatus for facilitating the preparation of warps for installation in the loom.

Preferably the apparatus is in the form of a transfer device for use in conjunction with warp drawing-in machines, such device being adapted to load or unload the machine with the warp, harnesses or other loom elements employed, and being of such a nature as to increase the capacity and output of such machines, and facilitate the work of drawing-in the warps thereon.

The invention will be best understood by reference to the following description when taken in connection with the accompanying illustration of one specific embodiment thereof, while its scope will be more particularly pointed out in the appended claims.

In the drawings:

Fig. 1 is a side elevation showing a transfer device with the warp beam, harnesses and reed in position for installation in a warp drawing machine;

Fig. 2 is a front elevation of the transfer device shown in Fig. 1;

Fig. 3 is a detail of the reed holder;

Fig. 4 is a detail in partial section showing the connection between the harness bar and its support; and

Fig. 5 is a plan view of the bracket or holder for the harness bar support.

Referring to the drawings and to the embodiment of the invention by which I have therein illustrated the same, there is shown one form of transfer device co-operatively associated by way of example with a well known type of drawing-in machine 1, the latter being of the same general construction as that shown in U. S. Patents Nos. 755,861, to Field; 871,860 to Field *et al.*; 862,474 to

Hathaway and 980,086 to Field, Lanning, Hathaway and Blanchard. Such machine is herein shown for the sake of illustration, it being obvious that the transfer device described with suitable modification may be usefully employed with warp drawing and other machines of widely different construction.

In the illustrated form of machine, as is well known to those skilled in the art, the loom elements, that is to say, the warp threads and those elements such as the harnesses, reed and drop wires, which accompany and are associated with the drawn-in warp for the control thereof in the loom, are supported in a generally parallel arrangement lengthwise the machine, while an appropriate needle or other thread placing device carried by a traveling carriage of the machine is caused to traverse the extent of the reed and harnesses and place successive warp threads through the desired heddle eyes and the selected reed dents, these being appropriately positioned for that purpose in the needle path by suitable selecting and positioning mechanisms.

The purpose of the invention is to provide a transfer device whereon the loom elements, such as the harnesses, reed and drop wires, which accompany and are associated with the drawn warp for the control thereof in the loom, may be supported in substantially the position which the elements are designed to occupy in the drawing-in machine, so that they may be installed therein on the said transfer device or may be withdrawn therefrom and maintained in such position or relation on the transfer device while examination for and correction of errors is subsequently made. The object furthermore is to provide a transfer device of such simplicity as to be inexpensive in construction and at the time capable of being collapsed or moved out of the way while not in use or during the drawing-in operation, so that while the transfer device still holds the warp beam there may be otherwise left a free unobstructed space for the machine operator.

Referring to the particular type of transfer device illustrated, the latter comprises a frame or platform consisting of the parallel channel irons 2 connected together and supported at each end upon pairs of swiveled trucks or casters 3. At one end there is provided a fixed upright bracket or standard 4

and near the opposite end a similar bracket 5, the latter, however, being longitudinally adjustable between the channel irons 2.

Each standard has fixed therein an upright bar 6 which through intermediate devices support the reed, harnesses and drop wires. To support the warp beam, each bracket is also provided with a warp beam holder consisting of a block 7 having the vertical stem 8 fitting a socket in the standard and adjustable vertically to different heights therein by means of the set screw 9. The block 7 has attached thereto the L-shaped member 10, to the upright arm of which are fastened the jaw teeth 11 and on the horizontal arm of which rests the supporting block 12 having inclined sides. The warp beam rests between the inclined block 12 and the jaw teeth 11, being held by its own weight from turning in such a direction as to permit unwinding of the warp threads. The upper side of the member 10 is toothed as shown and the lower edge of the block 12 has corresponding teeth. The member 12 has a depending tongue 13 passing through a slot in the member 10 so that the block can be fixed in different positions lengthwise the member 10, a transverse pin 14 on the tongue permitting the block to be lifted far enough to disengage the teeth but preventing complete withdrawal thereof from the member 10.

In installing the warp in the loom it may be required to turn the warp beam to slack the threads somewhat and to permit this to be readily accomplished, means are provided for lifting the warp beam free from the restraining influence of the jaw teeth 11. For this purpose a lifting lever 15 is provided pivoted at 16 on the holder, the end of the lever underlying the end of the warp beam and permitting the operator readily to lift the same. A fixed pin 16' on the holder working between projections on the lever limits both the up and down movement of the latter.

Referring to the devices for supporting the remaining loom elements, on each upright support 6 there is provided a vertically adjustable bracket 17 having upright ears or lugs 18 (see Figs. 2 and 5) between which is pivoted the horizontal supporting bar 19, the bracket 17 having an extension to provide an underlying rest 20 for the bar 19 so that the latter may be swung to a horizontal position where it is supported by the rest 20 as represented at the right hand side of Fig. 2, or swung up and back through approximately 270° where it hangs down at the side of and parallel with the bar 6 as shown at the left hand side of Fig. 2. The bars 19 serve as collapsible, inturned, horizontal, loom-element supports being directed inwardly over the warp beam when in position, but being adapted to be swung out of

the way into the collapsed position leaving the space intermediate the upright bars 6 substantially unobstructed by the harness and other supports. To support the harness bars, drop wires and reed, harness-supporting bars 21 are provided so connected to the inturned supports 19 as to be adjustable thereon at right angles thereto as represented in Fig. 1, or to be swung into parallelism therewith and hang down at the side 75 of the bar 6 as represented at the left hand side of Fig. 2 when the supports are collapsed.

A simple but effective connection between the bars 19 and 21 is shown in detail in Fig. 4. This consists of a thimble or cup 22 transversely slotted at 23 to receive the bar 21 and having a bottom perforated to receive the stud 24, the latter having the head 25 which seats in the bottom of the cup. The stud 24 in turn is slotted to receive the bar 19 and the end of the stud is threaded to receive the threaded nut 26 which is therefore adapted to be screwed upon the stud against the lower edge of the bar 19. The head 25 of the stud is drilled to form a socket for the sliding pin 27, which latter is interposed between the upper edge of the bar 19 and the lower edge of the bar 21. When the nut 26 is tightened it clamps the bars 21 and 19 with the intervening pin 27 tightly between the cap 22 and the nut 26. When the nut is loosened the connection is free to be slid along either bar in either direction and the bars are free to be swung to any required angle with each other or to a position of parallelism as shown at the left in Fig. 2. The connection between the bars therefore can be made at any position in the length of either one and they may be adjusted to any required angle permitting a universal adjustment to be obtained with a single connection, which, however, can be clamped fast with the single nut 26.

To support the reed a simple form of reed holder is provided, the same consisting of a notched portion 28 at the end of each rod 21 of sufficient size to receive the upper reed shaft.

The opening 28 is closed by means of a sliding pin or stud 29 which is normally pressed out to the position shown in Fig. 3 by means of the spring 30. By merely pressing the reed shaft up against the head of the stud 29, the latter is lifted to allow the reed shaft to move into the dotted line position therein shown. To release the reed it is merely necessary to press the stud 29 up against the spring 30.

To support the drop bars, notches 31 are provided on the under side of each harness supporting bar 21, thereby providing shoulders on which may be carried the stringer rods for the drop wires.

In utilizing the machine as a loading de-

vice the two supporting bars are swung up into the position shown at the right of Fig. 2 and adjusted to the required height, angle and position. The upper shafts of the harnesses are then laid across the harness supporting bars 21 in the relation they are intended to occupy in the drawing-in machine, the reed is placed in its holder and the drop wires, if any are employed, are also placed 10 in position by inserting their hanger bars in the notches 31. With the warp beam in position the transfer frame is then moved to a position at the rear of the warp drawing machine, as represented in Fig. 1, bringing 15 the harnesses, reed and drop bars in substantial registration with their holding devices in the warp drawing machine. The reed, harnesses and drop wires, being thereupon transferred to their supports in the 20 machine, the nuts 26 can be loosened permitting the arms 21 to be slipped back and then with the arms 19 to be swung down at the side of the bars 6 as shown at the left in Fig. 2. The warp threads being then stalled 25 in the machine, the drawing-in operation can proceed, there being no supporting parts carried by the truck to interfere with the machine operator.

To unload the warp drawing-in machine, 30 the operation is reversed, the rods 21 being moved to the position shown in Fig. 1 and the reed, harnesses and drop wires being again attached thereto carrying the drawn in warp. In this position the parts are withdrawn 35 from the machine permitting needed correction of errors to be made apart from the warp drawing-in machine, while the latter may be employed for drawing in a second warp.

40 If required, a supporting rod 32, carried by the vertically adjustable brackets 33 on the upright bar 6, may be employed to support the clamped ends of the warp threads and prevent them from falling down during 45 the installation of the warp in the warp frame or holder of the machine.

While for purposes of illustration we have herein shown and described one form 50 of the invention, it is to be understood that the same is not limited to details of construction or the relative arrangement of parts, but that extensive deviations may be made therefrom without departing from the spirit thereof.

55 Claims:

1. In a transfer device for a warp replenishing machine, the combination with a wheeled truck of relatively adjustable standards thereon, a warp beam holder on each 60 standard comprising a vertically adjustable holding member, a toothed jaw thereon, and an inclined rest for the warp beam.

2. In a transfer device for a warp replenishing machine, the combination with a 65 wheeled truck of relatively adjustable stand-

ards thereon, a warp beam holder on each standard comprising a vertically adjustable holding member, a toothed jaw thereon, an inclined rest for the warp beam, means for adjusting said rest, and means for lifting 70 the warp beam free from the teeth of said holder.

3. The combination with a warp drawing machine of a transfer device therefor having a truck, a warp beam, holder means for preventing turning of the warp beam, and means for freeing the warp beam therefrom to permit the installation of the warp in 75 the drawing-in machine.

4. In a transfer device for a warp drawing machine, the combination with a transfer frame, vertical end supports thereon, an inturned harness support on each vertical support, and pivotal holding means for said inturned support permitting the same to be 80 held in horizontal position or to be swung in parallelism with said vertical support.

5. In a transfer device for a warp replenishing machine, the combination with a transfer frame of an upright support, a harness supporting arm pivoted thereon, and adapted to hang in parallelism with said upright support, and means for holding it in 90 a horizontal supporting position.

6. In a transfer device for a warp replenishing machine, the combination with an upright support, a harness supporting bar pivotally supported thereon, and adapted for directly and individually receiving for transference thereto the harness bars, and a 100 rest for holding said harness supporting bar in harness supporting position.

7. In a transfer device for a warp drawing machine, the combination with a transfer frame of an upright support, a horizontal inturned support, and a harness supporting bar connected to said inturned support by means permitting angular adjustment and also a bodily adjustment along the inturned support.

8. In a transfer device for a warp replenishing machine, the combination with a harness supporting bar of a support for said bar, and a connecting clamp between the two permitting relative sliding movement between the clamp and each bar and also relative swinging movement.

9. In a transfer device for a warp replenishing machine, the combination with an upright support of an adjustable bracket thereon, a harness supporting arm pivoted on said bracket, and means for sustaining said arm in a horizontal position.

10. The combination with a warp drawing machine of a transfer device therefor, 125 the latter having a transfer frame, upright supports thereon leaving an intermediate unobstructed space, and a pair of arms on said supports adapted to be projected beneath the upper harness shafts and act 130

as a sole support therefor whereby said harness supporting arms may be placed in harness supporting relation to the upper harness shafts while the latter are in the warp drawing machine.

11. The combination with a warp drawing machine of a transfer device therefor having a transfer frame, harness supporting arms, and means at the ends of said arms for holding the reed.

12. The combination with a warp drawing machine of a transfer device therefor, the latter having a transfer frame provided with a pair of supporting arms each having its end recessed to receive a reed shaft, and means for closing the recess to hold the reed therein whereby the reed may be held suspended by the ends of said arms and held in substantially the same position which it occupies in the warp drawing machine.

13. The combination with a warp drawing machine of a transfer device therefor, the latter having a transfer frame provided with a pair of supporting arms each having its ends recessed to receive a reed shaft, and a spring-pressed pin to close each recess to hold the reed therein whereby the reed may be held suspended by the ends of

said arms and held in substantially the same position which it occupies in the warp drawing machine.

14. In a transfer device for a warp replenishing machine, the combination with a warp beam support of an upright support an arm, a second harness supporting arm sustained thereon, and means for securing said arms together comprising a clamping device permitting angular and longitudinal adjustment of one arm relatively to the other.

15. In a transfer device for a warp replenishing machine, the combination with a transfer frame of upright supports, a pair of supporting arms projecting therefrom and adapted to support one or more harnesses, each arm having its end recessed to receive the reed shaft, and a spring-pressed pin to close such recess.

In testimony whereof, we have signed our names to this specification, in the presence of two subscribing witnesses.

EDGAR F. HATHAWAY,
CHARLES LEA.
